(57) **CLAIM**

The ornamental design for a display screen or portion thereof with graphical user interface as shown and described.

DESCRIPTION

The FIGURE is a front view of a first embodiment of the claimed design of a display screen or portion thereof with a graphical user interface.

The outermost broken lines in the FIGURE illustrate a display screen or portion thereof and form no part of the claimed design. The remaining broken lines, including the closely-spaced broken line showing of text, numbers, and symbols, illustrate portions of the graphical user interface and form no part of the claimed design.
